UNITED STATES PATENT OFFICE.

HERMAN B. SCHMIDT, OF CINCINNATI, OHIO, AND OMAR T. JOSLIN, OF NEW YORK, N. Y.

APPARATUS FOR REFINING GLYCERIN.

SPECIFICATION forming part of Letters Patent No. 705,712, dated July 29, 1902.

Application filed April 9, 1897. Serial No. 631,393. (No model.)

To all whom it may concern:

Be it known that we, HERMAN B. SCHMIDT, a resident of Cincinnati, in the county of Hamilton and State of Ohio, and OMAR T. JOSLIN, a resident of the city, county, and State of New York, citizens of the United States, have invented certain new and useful Improvements in Apparatus for Refining Glycerin, of which the following is a specification.

Our invention relates to an improved apparatus for refining glycerin; and it consists in the peculiar arrangement and combination of parts illustrated in the accompanying drawings, in connection with which the invention will be first fully described and then particularly referred to and pointed out in the claims.

Figure 1 is a compound view of our apparatus, the heating-coils being shown in plan and the other parts partly in side elevation and partly in central vertical section. Fig. 2 is a transverse vertical sectional view of the still through line $x-x$ of Fig. 1 looking to the right. Fig. 3 is an elevation of the left end of the still. Fig. 4 is an elevation of the opposite end of the still. Fig. 5 is a detail view, in diametrical section and upon a greatly-enlarged scale, of one section of the separator, a part of the shelf or trough being broken away to expose the parts back of the upwardly-projecting flange.

Referring to the parts, which are indicated by similar reference-letters wherever they occur throughout the various views, A represents the outer shell of the still, which is supported upon feet a. The part A has outwardly-projecting flanges a' upon each end to form seats for the heads a² and a³, which are secured to the shell A by bolts or screws passing through the heads and tapped into the outwardly-projecting flange. The shell A has cast integral with it an interior cylinder A', which is connected to the outer cylinder by partitions a⁴ and also inwardly-projecting baffle-plates a⁵. The heads a² and a³ have perforated bosses a⁶ and a⁷, either cast integral with the heads or secured thereto in any well-known manner. These bosses form bearings for the hollow journals of the inner revolving cylinder B, one of the protruding

journals being provided with a gear-wheel b, which meshes with the pinion b', secured upon a driving-shaft b², which shaft is also provided with tight and loose pulleys b³ and b⁴, 55 which are driven by a belt which receives its power from any suitable source.

The hollow journals of the cylinder B have swivel-couplings b⁵ upon their ends, to the inner one of which is connected the pipe b⁶, 60 which conducts the heating agent (preferably oil) from the heating-coil b⁷ to the interior of the cylinder, and the other receives the pipe b⁸, which conducts the heating agent from the cylinder to the jacket or chamber between 65 the outer shell A and the inner shell A' and the partition a⁴. The heating agent is carried from the jacket through the pipe b⁹ back to the coil b⁷ to be reheated by the pump C.

The cylinder B revolves in the glycerin, 70 which is supplied to the bottom of the cylinder A' through a pipe b¹⁰, the amount being regulated by a cock interposed in the pipe, and the purpose of the lower jacketed space between the partitions a⁴ is to prevent the 75 heating agent from coming in contact with that part of the cylinder A' which contains the glycerin and forming a scale or decomposing and burning the liquid to be distilled. The liquid to be distilled is carried up in a 80 thin film around the revolving cylinder and is met by a current of steam, which is superheated by passing through a cast-iron coil D, thence through the pipe d, which has a return-bend within the terminal b¹¹ of the coil 85 b⁷. The pipe d enters the cylinder by means of suitable couplings through the head a³, and the part of it within the cylinder A' is perforated along its entire length to discharge the steam against the cylinder and downwardly in the direction of the liquid to be distilled. By placing the perforated pipe in the position shown the jets of steam are discharged above the liquid in the still, by which the foaming so objectionable in all other processes is entirely prevented; but it would be an inferior modification of our invention to immerse the perforated pipe in the liquid. 90

The purpose of the baffle-plates a⁵ is to interrupt the current of steam which is admitted into the cylinder A' and deflect it against the liquid carried up on the revolving cylinder. 95

der, and the purpose of placing the steam-pipe inside of the terminal coil, through which the heating medium for the still passes, is to bring the steam to the same temperature as 5 the oil or other heating medium before it enters the cylinder A.

In order to present a clean bright surface to the revolving cylinder which carries up a film of the liquid to be evaporated, we have 10 provided a thin blade or scraper E, which is mounted upon a rod secured in the cylinder-heads and bears with spring-pressure against the periphery of the revolving cylinder B throughout its full length, thus preventing 15 the formation of any scale or sediment upon the periphery of the revolving cylinder. Any sediment from the glycerin settling in the bottom of the cylinder A' may be drawn off or discharged through the pipe a⁸.

20 In the still the glycerin carried up by the revolving cylinder is distilled and mingles with the superheated steam and both distilled over together through the pipe f to the bottom section of the separator F. The separator is composed of a series of flanged sections f', (shown upon an enlarged scale in Fig. 5,) each section having outwardly-projecting flanges, by means of which the sections are bolted together to form the separator F. Each section has an inwardly-projecting shelf f², which, with its upwardly-extending flange f³, forms an annular trough around the inner wall of the section. Each section is provided with a cap G, which extends over the 35 inner wall of flange f³ of the gutter and is supported above the shelf f² by feet or angle-plates f⁴, which are riveted upon the shelf and to the downwardly-curved flange of the cap G. Through the shelf of each section, but on alternate sides, is a drip-pipe f⁵, the upper end of 40 which extends to a plane slightly below the upper edge of the flange or inner wall of the gutter f³ and above the lower edge of the cap G to form a seal and prevent the escape of 45 the vapor after passing through the glycerin in the shelves. The distillate entering the lower section is deflected by the cap G into the gutter. The glycerin being the heavier substance fills the gutter up to the top of the 50 pipe f⁶. The unseparated vapors passing to the section above are again conveyed to the gutter until all the gutters are filled up to the top of the pipe f⁶ with the separated glycerin, after which the vapors bubble through 55 the layer of liquid in the troughs and the separated glycerin overflowing from one trough to the other drips into the cone-shaped bottom of the separator and is then from there conveyed through a pipe f⁷ to the receiving-drum f⁸. To the top f⁹ of the separator is secured the condenser H, which consists of the pipe h, through which the escaping steam from the separator is drawn, as shown, by the vacuum-pump J. The condenser is the cylinder H, surrounding this pipe h, and through the jacket between the pipe and outer shell of the condenser a stream

of cold water is run, entering at the pipe h' and passing out through the pipe h². The object of the condenser is to condense a portion of 70 the escaping steam and return it to the top plate G of the separator to keep it cool. The upturned bends of the pipes f⁵ serve as traps to prevent the vapor from passing up through them.

The heating-coils (shown in Fig. 1) are arranged in a furnace-wall (indicated in dotted line) with a grate below to receive the fuel, an arrangement (not shown) by which the heat can be controlled, so that the heating 80 medium when it enters the revolving drum can be kept at any desired temperature. It is not deemed necessary to use any particular form of furnace for heating the coils, as any well-known furnace may be used for this 85 purpose.

The operation of the apparatus is as follows: The heating medium for the revolving drum (preferably oil) is heated by the fire in the furnace, and the circulation is supported 90 by means of the pump C, first through the heating-coils, then through the revolving drum, thence through the jacket around the drum, and back again to the heating-coils. The fire in the furnace is so controlled that 95 the temperature of the heating medium as it enters the revolving drum is that found most suitable for the liquid to be distilled. The liquid to be distilled is now run into the cylinder A', forming a shallow layer at the bottom thereof. The drum revolving carries a thin film of this liquid up, at the same time heating it to the distilling-point. The steam, which is preferably superheated to the temperature of the heating medium by passing 105 through the coil D and the terminal of the coil b⁷, passes into the interior of the still over the surface of the drum, the contact of which is facilitated by the baffle-plates a⁵, and escapes, thoroughly saturated with the vapors 110 of the distillate, through the pipe f to the separator F. This vapor, entering the lower section of the separator, passes through the various sections from the bottom to the top 115 through the successive compartments. During this passage the vapor is gradually deprived of the valuable parts of the distillate until it leaves at the top, steam only escaping through the condenser H. A small portion of the steam only is condensed in the pipe h 120 and flows back to the top of the upper plate, thus preventing the escape of any glycerin.

By means of the above-described arrangement a distillate of any desired gravity can be drawn off from the bottom of the separator. 125

It is obvious that some parts of our invention, particularly the still and separator, may be employed with other structures and that an inferior modification of the still might be produced by omitting some of its parts. We 130 have shown what we believe to be the best means of carrying out our invention; but from an examination of the same it would be obvious to those skilled in the art to which this

invention relates that many mere mechanical changes may be made in some of the parts without departing from the spirit or scope of our invention. We therefore do not limit ourselves to the precise details shown.

What we claim, and desire to secure by Letters Patent, is—

1. In a still the combination of the outer case, a drum mounted to revolve therein, said drum having hollow journals extending to the outside of the case to receive and pass the heating medium for said drum, the heating-coil, pipes from said heating-coil to convey the heating medium to and from said drum, a pump interposed in one of said pipes to cause the heating medium to circulate through the drum and heating-coil, a pipe to convey the liquid to be distilled to the bottom of the case and in contact with the revolving drum, and a pipe to convey the distillate from the case, whereby a thin film of the liquid is taken up by the drum, distilled by its heating, and the distillate passed from the case, substantially as shown and described.
2. In a still the combination of the outer case, an interior case forming a jacketed space between the outer and inner case, partitions for dividing the jacket into two chambers, the upper one to receive the heating medium and the lower one to exclude the heating medium from that portion of the case which contains the liquid to be distilled, a drum mounted to revolve in the case said drum having hollow journals to receive and pass the heating medium into and from said drum, a heating-coil, pipes from the terminal of said coil, one of said pipes to connect with one of the hollow journals of the revolving drum and the opposite coil to connect with the jacketed space surrounding the upper part of the drum, a pipe to connect the opposite hollow journal with the said jacketed chamber, a pump interposed in the supply-pipe for the drum to create a circulation for the heating medium through the drum and chamber, and pipes to convey the liquid to be distilled to the bottom of the case and in contact with the revolving drum and discharge the distillate from the case, substantially as shown and described.
3. In a still the combination of the outer case, an interior case forming a jacketed space between the outer and inner case, partitions for dividing the jacket into two chambers, the upper one to receive the heating medium and the lower one to exclude the heating medium from that portion of the case which contains the liquid to be distilled, a drum mounted to revolve in the case said drum having hollow journals to receive and pass the heating medium into and from said drum, a heating-coil, pipes from the terminal of said coil, one of said pipes to connect with one of the hollow journals of the revolving drum and the opposite coil to connect with the jacketed space surrounding the upper part of the drum, a pipe to connect the opposite hollow journal with the said jacketed chamber, a pump interposed in

the supply-pipe for the drum to create a circulation for the heating medium through the drum and chamber, pipes to convey the liquid to be distilled to the bottom of the case and in contact with the revolving drum and discharge the distillate from the case, a coil for superheated steam, and a pipe from said coil passing into the case end and across the case parallel with the revolving drum, said pipe being perforated its entire length within the case to discharge jets of superheated steam above the liquid to be distilled and against the drum, substantially as shown and described.

4. In a still the combination of the outer case, an interior case forming a jacketed space between the outer and inner case, partitions for dividing the jacket into two chambers, the upper one to receive the heating medium and the lower one to exclude the heating medium from that portion of the case which contains the liquid to be distilled, a drum mounted to revolve in the case said drum having hollow journals to receive and pass the heating medium into and from said drum, a heating-coil, pipes from the terminal of said coil, one of said pipes to connect with one of the hollow journals of the revolving drum and the opposite coil to connect with the jacketed space surrounding the upper part of the drum, a pipe to connect the opposite hollow journal with the said jacketed chamber, a pump interposed in the supply-pipe for the drum to create a circulation for the heating medium through the drum and chamber, pipes to convey the liquid to be distilled to the bottom of the case and in contact with the revolving drum and discharge the distillate from the case, a coil for superheated steam, and a pipe from said coil passing into the case end and across the case parallel with the revolving drum, said pipe being perforated its entire length within the case to discharge jets of superheated steam above the liquid to be distilled and against the drum, and a scraper to bear against the periphery of the drum for preventing the formation of scale or sediment on the surface of the drum, substantially as shown and described.

5. In a still the combination of the outer case, an interior case forming a jacketed space between the outer and inner case, partitions for dividing the jacket into two chambers, the upper one to receive the heating medium and the lower one to exclude the heating medium from that portion of the case which contains the liquid to be distilled, a drum mounted to revolve in the case said drum having hollow journals to receive and pass the heating medium into and from said drum, a heating-coil, pipes from the terminal of said coil, one of said pipes to connect with one of the hollow journals of the revolving drum and the opposite coil to connect with the jacketed space surrounding the upper part of the drum, a pipe to connect the opposite hollow journal with the said jacketed

chamber, a pump interposed in the supply-pipe for the drum to create a circulation for the heating medium through the drum and chamber, pipes to convey the liquid to be distilled to the bottom of the case and in contact with the revolving drum and discharge the distillate from the case, a coil for superheated steam, and a pipe from said coil passing into the case end and across the case partition with the revolving drum, said pipe being perforated its entire length within the case to discharge jets of superheated steam above the liquid to be distilled and against the drum, and baffle-plates extending inward from the case to interrupt the current of the steam and deflect it against the periphery of the revolving drum, substantially as shown and described.

6. The combination of the separating vessel composed of a series of flanged sections having inwardly-projecting flanged troughs, said sections being secured together one above the other, heads covering the top and bottom of the sections, caps extending over the flanged upturned inner edges of the gutters and supported above the bottom or shelf of the gutter, pipes passing through the troughs, extending up into them and having

their lower ends bent to prevent the vapors passing through said pipes and receiving vessel of the separator, an exhaust-pipe for the separated steam at the top thereof, a cooling-chamber surrounding said pipe and having inlet and outlet pipes for the cooling-water to condense a portion of the steam and prevent the escape of glycerin, and an inlet-pipe for the heated vapors in the lower section of said separator, substantially as shown and described.

7. A plant for purifying glycerin consisting of a still in which the vapor of glycerin is mingled with superheated steam, coils for heating the medium and superheating the steam which passes into the still, a separator to separate the vapors of glycerin and steam, and the pipe connecting the vapor-chamber of the still with the lower part of the separator, substantially as shown and described.
